CLAIM

The ornamental design for a card payment terminal, as shown and described.

DESCRIPTION

FIG. 1 is a perspective view showing our new design for a card payment terminal;

FIG. 2 is a front view thereof;

FIG. 3 is a rear view thereof;

FIG. 4 is a top plan view thereof;

FIG. 5 is a bottom plan view thereof;

FIG. 6 is a left side view thereof;

FIG. 7 is a right side view thereof; and,

FIG. 8 is a perspective rear view illustrating the card payment terminal of the present invention in its environment of use.

The portions shown in broken lines are solely for the purpose of illustrating context and environmental structures only and form no part of the claimed design.

1 Claim, 8 Drawing Sheets(56)
